(57) **CLAIM**

The ornamental design for an electric connector, as shown and described.

DESCRIPTION

FIG. 1 is a front view of an electric connector showing our new design;

FIG. 2 is a rear view thereof;

FIG. 3 is a left side view thereof;

FIG. 4 is a right side view thereof;

FIG. 5 is a top plan view thereof;

FIG. 6 is a bottom view thereof;

FIG. 7 is a perspective view thereof; and,

FIG. 8 is a reference perspective view thereof showing a condition in use.

The broken line showings of FIG. 8 are environmental only and not part of the claimed design.
